UNITED STATES PATENT OFFICE

FRANK THOMAS, OF INDIANAPOLIS, INDIANA

DESIGN FOR AN AMUSEMENT HOUSE

Application filed November 12, 1926. Serial No. 19,693. Term of patent 14 years.

To all whom it may concern:

Be it known that I, FRANK THOMAS, a citizen of the United States, residing at Indianapolis, in the county of Marion and State of Indiana, have invented a new, original, and ornamental Design for an Amusement House, of which the following is a specification, reference being had to the accompanying drawings, forming part hereof, in which

I claim:

The ornamental design for an amusement house, as shown.

FRANK THOMAS.
